AUTOMOBILE RADIO ANTENNA

Claude C. Farwell, Groton, Mass.

Application November 17, 1938, Serial No. 240,988

2 Claims. (Cl. 250—33)

Among the objects of the invention are to provide an antenna having—

High efficiency in signal pickup;

One that may easily be applied to any car;

5 One that will present a neat and attractive appearance and harmonize with the fittings of the modern car;

One that does not normally extend above the top of the car, but is capable of extension for 10 obtaining better pickup capacity if desired; and

One that permits of a very short easily shielded lead-in from the antenna to the radio set.

The invention can best be seen and understood by reference to the drawings in which examples are shown and in which—

Fig. 1 shows in front elevation an automobile with one example of the antenna applied to it.

Fig. 2 is a cross section of a detail of construction to which special reference will later 20 be made.

Fig. 3 is a front elevation of certain parts shown in Fig. 2.

Fig. 4 is a side elevation of a detail of construction.

25 Fig. 5 is a cross section of a modified detail of construction.

Fig. 6 is an elevation of another example of the antenna.

Fig. 7 is an elevation of the antenna shown in 30 Fig. 6 when applied to the automobile; and

Fig. 8 is an elevation of another example of the antenna along the lines of that shown in Fig. 7 but embodying a modified construction.

In the drawings 1 represents the cowl of an 35 automobile, 2 the windshield. Attached to the cowl just below and in front of the windshield, on the opposite sides of the cowl, are brackets 3 with arms 4 outstanding from the body of each bracket. Each bracket is secured to the cowl by bolts 5 passed through its body and through the metal of the cowl and retained by nuts 6 inside the cowl. Formed within the body of each bracket is a hole 7 which in the attached bracket is continued through the metal of the cowl and 40 through this hole the lead-in wire 8 is extended to connect with the radio set (not shown).

Set into the arms 4 of the brackets are insulating grummets 10 of any suitable insulating material. Passed through the arms 4 thus fitted 50 with grummets, are rods 12, which are insulated from the brackets by the grummets. The lower end of each of the rods is threaded, where the rod extends through the lower arm of the bracket and contained grummet, and arranged upon this 55 threaded end of the arm are nuts 13, 13 which

tighten against the grummet and arm of the bracket fixing the rod securely in place.

The rods 12 are preferably arranged by the setting of the brackets to extend vertically upward although they may be inclined if desired towards 5 the windshield. The rods 12 extend telescopically into tubes 14. These tubes are provided each with a right angular bend 15 in it whereby the free ends of the combined tubes will point inwardly towards one another across the cowl well 10 above it, and in front of the windshield. Connecting and telescopically contained in part within the free ends of the tubes thus extending is a rod 16.

At the point where a rod extends telescopically 15 into a tube the rod is securely fixed to the tube. The end of the tube into which the rod is entering is provided with a split 18, and threaded. Arranged upon this threaded and split end of the tube and, also, upon the entering rod is a 20 coupling 20. This coupling has a slip fit upon the rod and beyond, where the coupling engages the split end of the tube, the interior of coupling is threaded and made slightly tapering so that when the coupling is screwed on to the end of 25 the tube it will bind the split end of the tube hard against the contained rod thereby fixing the rod and tube securely together in any telescopically adjusted position.

Inasmuch as each of the uprights of the antenna is composed of a rod and tube into which the rod telescopically extends to be there fixed in any telescopically adjusted position, consequently the antenna where it crosses the cowl may be raised to a point either below the top 30 of the car, or be raised to a point within the telescopic limits of the uprights, thus providing an antenna which rises well above the top of the car and gives better pickup for radio waves under conditions where reception is hard to obtain. Likewise that portion of the antenna which crosses the cowl is composed of rod and tube into which the rod telescopically extends to be fixed in any telescopically adjusted position, and this 40 permits of precise lateral adjustment according to the width of the car.

In assembling the antenna and attaching it to a car the brackets 3 are first fixed to the cowl and the rods 12 set in the brackets. The tubes 50 14 and interposed rod 16 are then combined and adjustably fixed by the couplings according to the width of the car and then the tubes are slipped down over the rods 12 and fixed thereto by the couplings. Afterwards the lead-in wire 55

8 is connected to one of the rods 12 acting as a post.

While reference has been made to the elements 12 as rods they may, in fact, be tubes, or tubular rods (as shown in Fig. 5), instead of solid rods. In fact, it is better that all the telescopic elements be tubing for tubing has less radio frequency resistance than does solid rod. It is obvious that considerable variation may be made in the series 10 of elements forming the antenna and the manner of their telescopic connection. For example, in Figs. 6 to 8, inclusive, a construction is shown in which the telescopic elements of the antenna are connected without the need of couplings, and 15 this through frictional engagement between the elements themselves, and this admitting, also, of the elements being arranged in any determinate adjusted position.

In Fig. 6 there are shown tubes 22 having bends 20 therein into the opposing end portions of which telescopically fits a tube or rod 23. The initial formation or bending of the tubes 22 is such that, with the contained tube 23 in their respective 25 ends, those portions 22¹ of the tubes 22 which form the uprights to the antenna occupy an angular outwardly turned position with relation to each other. When these portions 22¹ of the tubes 22 are moved in so as to be attached, as before 30 described, to the brackets 3 on the sides of the car strain will consequently be thrown upon the interposed tube 23 and this tube will be bent. In consequence of such bending or distortion its ends will be frictionally retained within the end portions of the tubes 22 in any determinate adjusted 35 position (see Fig. 7).

Instead of attaching the end portions 22¹ of the tubes 22 to the brackets the tubes may be brought in to telescopically engage tubes or rods 24 fixed to the brackets (as shown in Fig. 8), 40 thus permitting of the raising of the antenna as previously described. The tubes 22 will then be made to frictionally engage the elements 24 and be maintained in any determinate adjusted position thereon for the reason that the bending or 45 distortion of the connecting element 23 will throw such strain upon the elements that not only will the element 23 be frictionally retained within the

opposing ends of the elements 22 as previously described, but these elements themselves will be thrown into hard frictional engagement with the fixed elements 24 and will consequently maintain any determinate adjusted position upon these 5 elements.

The telescopic elements of the antenna are preferably made of copper and they together with the brackets may be chromium plated or otherwise finished to correspond with the finish of 10 the car.

I claim:

1. A radio antenna for an automobile having a windshield and cowl adjacent thereto comprising a series of elements telescopically connected including opposing elements having bends therein and into the opposite end portions of which the end portions of an interposed element is telescopically contained, means whereby said opposing elements may be insulatingly connected to the opposite 15 sides of said cowl, said opposing elements being so initially formed in relation to said interposed element that said interposed element will be sprung upon fixing said opposing elements to said cowl and the frictional engagement between its 20 ends and said opposing elements be tensionally maintained.

2. A radio antenna for an automobile having a windshield and cowl adjacent thereto comprising a series of elements telescopically connected 30 including upright elements, opposing elements having bends therein in telescopic engagement with said upright elements and into the opposite end portions of which opposing elements the end portions of an interposed element is telescopically contained, means whereby said upright elements may be insulatingly connected to the opposite sides 35 of said cowl, said opposing elements being so initially formed in relation to said interposed element that said interposed element will be sprung upon bringing said opposing elements into 40 telescoping engagement with said upright elements when connected to the cowl as aforesaid and the frictional engagement between all of said elements be tensionally maintained.
